UNITED STATES PATENT OFFICE

1,935,888

DOUBLE WALLED CONTAINER

Walter J. Podbielnak, Tulsa, Okla.

Application June 12, 1931. Serial No. 543,969

4 Claims. (Cl. 202—223)

The present invention relates to improvements in double walled containers, the inner and outer walls of which may be exposed to different temperatures, and more particularly to elongated, evacuated containers or jackets employed as insulating jackets for fractional distillation columns or as the columns themselves. The invention will be more fully understood from the following description thereof, illustrated by the accompanying drawing, in which:

Figure 1 is a sectional view, partly broken away, through a distillation apparatus provided with a vacuum jacketed container embodying the present invention; and

Fig. 2 is a detail sectional view upon an enlarged scale, partially broken away, of portions of the inner wall of the evacuated container as seen at the left side of Fig. 1.

Referring more particularly to the drawing, which shows a distillation apparatus of the type more fully described in my prior applications 475,584 and 475,585, both filed August 15, 1930, the numeral 5 designates a distillation column, the lower end of which is enlarged to form a distilling bulb 6, provided at its lower end with a constricted elongated portion 7 to which heat may be applied, for example, by the electrical heating element 8.

Surrounding the distilling tube 5 for substantially its entire length, there is an evacuated, double walled container or jacket 9, constructed in accordance with the present invention as more fully hereinafter described, and serving as an insulating jacket for the distilling tube. At its lower end, the jacket member 9 is enlarged, as at 9^a, to surround the distilling bulb 6. At the lower end of the jacket 9, the distilling tube 5 may be held in position by a suitable cork or washer 10 and also, if desired, by packing material 11 surrounding the lower end of the distilling bulb 6.

At the upper end of the double walled jacket 9, it is enlarged, as at 9^b, and in the enlarged space thus provided around the upper end of the distillation column 5, a container 12 of annular cross section is provided, surrounding the column 5. Inlet and outlet pipes 13 and 14 are provided, leading into and out of the chamber 12 for the supply and removal of a cooling medium, and suitable packing, such as at 15, may be supplied within the annular cooling chamber 12 for distribution of the cooling medium when a vaporizable material, such as liquid air, is employed for the purpose. The column 5 may be supported in relative position in the upper portion 9^b of the jacket 9 by means of a suitable perforated cork or washer

16 and packing may be provided within the enlarged upper portion 9^b of the jacket surrounding the column 5 and the chamber 12, as shown at 17.

The double walled jacket 9, with its enlarged end portions 9^a and 9^b has hitherto been constructed of glass, preferably a low-expansion, heat resistant glass of the borosilicate or other readily available type, such as that commercially known as "Pyrex", and provided with silver mirrors on one or both of the inner walls, thus forming, on evacuation, an efficient insulating jacket. In use, however, the inner wall 18 of the jacket 9 is subjected to a wide range of temperature variations, particularly the long, central straight portion thereof, while the outer wall is subjected to a relatively minor range of temperature variations, ordinarily but little above or below the normal surrounding atmospheric temperatures. The variations in temperatures to which the inner wall of such an insulated container are subjected may be even greater when the inner wall is itself employed as the distillation column. The temperature variations may be from temperatures of -400° F. (or lower) to +300 to 400° F. (or higher) in the analytical distillation of natural gas hydrocarbons and natural gas gasoline, and temperatures very considerably higher, say to 500 to 600° F. may be reached in the distillation of kerosene, naphthas, or other liquid petroleum products.

As a result of the great differences in the temperature variations to which the inner and outer walls of the double walled jacket 9 are subjected, as hitherto constructed, there have been great differences in the expansion and contraction of the inner wall 18, and particularly the elongated central portion thereof, with respect to the remaining portions of the jacket or container 9. To a certain extent these variations may be taken care of by a slight bowing of the inner wall 18, the curvature of the wall decreasing as the temperature of the inner wall drops relative to the outer wall and increasing as it rises. However, and particularly when very great temperature variations may be present, such variations in curvature of any bow or arch that may be provided in the inner wall 18 may not be sufficient to avoid impairment or breakage of the apparatus.

In accordance with the present invention, the inner wall 18 of the double-walled container or jacket 9 is formed of fused quartz, the transparent fused quartz being preferably employed. While the entire inner wall of the jacket 9 may be constructed of quartz, it is preferred to use quartz in its construction only from about the

point of the upper enlargement of the container 9 at 9^b, say the point 18^a to the lower end of the inner wall, as at 18^b, this being the portion of the apparatus subjected to the greatest variations 5 in temperature. At these points, the inner quartz tube is joined to the low-expansion glass of which the remainder of the container is constructed by any suitable sealing means, for example, by what is known in the glass blowing art as a "graded joint" built up by fusion of particles of quartz and the glass employed with gradually increasing proportions of glass. The points where these graded joints are provided are indicated in the drawing at 18^a and 18^b.

15 It is readily apparent that the inner, quartz tube portion of the container or jacket 9 made in accordance with the present invention may be slightly bowed, if desired, and that the walls of the jacket or container 9 may be provided with 20 mirrors internally, if desired. By constructing the inner wall, which is exposed to the widest range of temperature variations, of quartz, the variations in its length due to expansion and contraction are markedly reduced and more nearly 25 equalized with those taking place in the outer wall of the container or jacket. It is readily apparent that if the container or jacket is to be used under circumstances wherein the outer wall of the container or jacket are subjected to the 30 greatest variations in temperature, the outer wall will be formed of quartz, joined or sealed to the low expansion glass or other glass forming the remainder of the device. Furthermore, it is readily apparent that in many cases, it will not 35

be necessary to use the low-expansion type of glassware in constructing those portions of the jacket not exposed to wide temperature variations.

I claim:

1. An elongated, double walled, insulating container adapted to have a wall portion thereof subjected to marked variations in temperatures, said wall portion being formed of fused quartz and the remainder of said container being formed of low-expansion, heat-resistant glass joined and sealed to said quartz. 80

2. A double walled, evacuated container of elongated columnar form, an inner wall portion of said container being formed of fused quartz and the remainder of said container being formed of glass, joined and sealed to the quartz inner wall portion thereof. 90

3. In distillation apparatus, a double walled, evacuated container of elongated, cylindrical form, the inner wall of said container being adapted to be subjected to marked variations in temperature, said inner wall being formed of fused quartz and the remainder of the container being formed of glass joined and sealed to said quartz inner wall. 95

4. In distillation apparatus, an elongated distillation column for containing the material to be distilled, a double-walled, evacuated container surrounding said column, the inner wall of said container adjacent the column, being formed of fused quartz and the remainder of the container being formed of low-expansion glass joined and sealed to said quartz inner wall. 105
